Attorneys.

UNITED STATES PATENT OFFICE.

CHARLES F. FREAY, OF KENNEDY, NEW YORK.

DROP-SAW MACHINE.

Application filed December 5, 1919. Serial No. 342,690.

To all whom it may concern:

Be it known that I, CHARLES F. FREAY, citizen of the United States, residing at Kennedy, in the county of Chautauqua and State 5 of New York, have invented certain new and useful Improvements in Drop-Saw Machines, of which the following is a specification.

This invention relates to drop saw machines, that is to say, it belongs in the class 10 with those wood-sawing mechanisms which are provided with a saw in a frame having one end pivoted, enabling the saw to be raised and lowered to cut logs or timbers fed 15 beneath it by suitable contrivances.

It is the object of this invention to produce a machine of the character stated wherein are combined parts of special construction and arrangement, and which is 20 provided with a single operating lever that controls the feeding devices by horizontal movements, and by a vertical movement brings into action the members by which the saw and its frame are raised.

To illustrate the construction and arrangement of the parts of this invention, the accompanying drawings are made a portion 25 of this application. Fig. 1 is a top plan view of all the parts assembled. Fig. 2 is a side 30 view of the operating lever showing the construction of its vertically movable fulcrum. Fig. 3 is a side view of the belt pulleys and relating parts, the saw shaft and feed drive shaft being in section. Fig. 4 is a front view 35 of the supporting frame, showing the manner of suspending the saw frame, and the winding drum and clutch on the saw shaft.

Throughout the drawings and description 40 the same numerals are used to refer to the same parts.

Considering the drawings, a base frame is formed by the beams 1, 2, 3, 4, 5 and 6 which carry the operating parts. It will be understood that this invention is not confined to 45 the particular construction of the base frame set forth. The transverse shaft 7 is the feed drive shaft, and carries a sliding sleeve 8. The sleeve is moved back and forth upon the shaft by the fork 9 of the operating lever 50 10 the fulcrum of which engages the vertical rod 11. The fork end 9 of the lever engages the annularly grooved member 12 on the sleeve 8, and the sleeve carries the oppo-

sitely disposed gears 13 and 14. The gear 15 is a part of the feeding device mechanism 55 and is placed as shown in Fig. 1, in the path of the sliding gears, in order that the feeding devices may be operated in either direction, depending upon which of the sliding gears is moved into mesh by the horizontal 60 movement of the lever. The gear 15 is located on the end of the shaft 16 which is supported in bearings 17 and 18. At the other end of the shaft 16 is a bevel gear 19 engaging a like gear 20 on transverse shaft 21, which shaft 65 is supported in bearings 22 and 23. At the end of shaft 21 is a bevel gear 24 that engages the like gear 25 on shaft 26. The shaft 26 has the bearings 27 and 28, and carries the drum 29 provided with spikes 30 for 70 feeding the timbers beneath the saw. The drum 29 is usually lessened in diameter in the middle as illustrated to better position the timber to be sawed.

Power is applied to the working members 75 by the belt 31 which engages both the top and bottom of the pulley 32 on the feed drive shaft 7, as shown in Fig. 3. The belt is held upon the upper portion of the pulley by means of the weighted idler roller 33, on 80 stub shaft 34, carried by arm 35 supported in bearing 36 upheld by the standard or legs 37.

The saw frame comprises the converging beams 38 and 39 through which the shaft 7 passes, and the cross piece 40 and tie bolts 85 41 and 42 connect the beams at their outer ends. The passing of the shaft 7 through the beams 38 and 39 pivotally supports their ends, enabling the outer end to be raised and lowered as will be readily understood. The 90 saw 43 is carried on the outer end of the saw shaft 44 in bearings 45 and 46, and the saw shaft carries the pulley 47 about which the belt 31 passes as shown and by which the saw 95 is driven.

The saw shaft is supported by tackle connected with a supporting frame 48 having the cross-piece 49. The tackle comprises the cord 50 having one end connected with the fastening 51 on bearing 45, and passing 100 thence over cord pulley 52 on the yard or cross-piece 49, thence around the pulley 53 attached by the hanger 54 to the bearing 45, thence around the pulley 55 on the cross piece, thence around the pulley 56 attached by 105 hanger or shank 57 to the bearing 46, thence

around the pulley 59 attached by the hanger 58 to the cross piece, thence downwardly and around the hoisting drum 60, and upwardly around the pulley 61 and 62, below which the end of the cord 50 is attached to the weight 63. The hoisting drum 60 is loose on the saw shaft 44, and it may be connected operatively with that shaft when desired by a vertical movement of the operating lever 10. As shown in Figs. 1 and 2, the cord 64 is connected to the lever, and passes downwardly through the eye 65 on the beam 2. From the eye the cord 64 passes upwardly around the pulley 66 on the side beam 39 of the saw frame, and thence to the fastening 67 on the clutch-operating arm 68. The arm is held outwardly from the beam 39 by the coil spring 69. The function of the spring-returned arm 68 is to move the collar 69^a on the saw shaft into contact with the loose drum 60, which it slides along the shaft until the members 70 and 71 of the clutch are engaged and the power of the saw shaft applied to the hoisting drum.

In the operation of this invention, the horizontal movements of the lever 10 on the pivot rod 11 bring either gear 13 or 14 at will into mesh with the interposed gear 15 of the log-feeding devices, and the log or timber may be moved in either direction as desired. If the outer end of the lever 10 be raised its fulcrum will slide up the pivot rod or pin 11, and the cord 64 will be drawn upon. This causes the arm 68 to close the drum 60 against the clutch members, and the saw shaft will revolve the drum thereby drawing upon the cord 50 and raising the saw, the weight 63 descending at the same time. It is intended that the weight shall sufficiently balance the weight of the saw and frame, to enable the frame to be held up by hand when the motor is stopped. When the motor is running and the saw is raised by the power, the feeding devices are set in motion at the same time, and the timber fed to the required extent for the next cut. It will be noted that the lever may be moved horizontally whatever its position upon the pivot pin 11. When the lever is lowered, the drum and saw shaft are disengaged, and the saw descends and saws the timber. This operation of raising the saw, and feeding the timber is carried out repeatedly and conveniently by the operator who needs to use but the one lever either to feed the timber or to raise the saw. The operator stands near the outer end of the lever from which position he can readily see when the timber or log is correctly positioned, and he can feed the timber to be cut into any desired lengths. In practice this invention is constructed of such size and weight as will permit it to be loaded upon a truck, and transported from place to place wherever

there is timber to be sawed. The power is usually derived from a gasoline engine carried with the machine.

Having now described this invention, and explained the mode of its operation, what I claim is: —

1. In a drop saw machine, the combination with feeding devices, of a saw frame having one end pivotally supported, a saw shaft and saw, a pulley on the saw shaft, 75 an independently driven belt for revolving the pulley, a feed drive shaft, a pulley on said drive shaft, the said belt engaging the said pulley and actuating the feed drive shaft, reversible means for engaging and disengaging said drive shaft and feeding devices, a lever movable in a predetermined direction for operating the said engaging means, and means driven by said saw shaft and controlled by the movement of said 80 lever in another direction for raising the saw.

2. In a drop saw machine, the combination with feeding devices, of a saw frame having one end pivotally supported, a saw shaft and saw, a pulley on the saw shaft, 90 an independently driven belt for revolving the pulley, a feed drive shaft, a pulley on the drive shaft, the said belt engaging the said pulley and actuating the said drive shaft, 95 gears oppositely disposed and arranged to slide together on said drive shaft and driven by the shaft, devices for sliding the said gears back and forth on the drive shaft including a horizontally movable lever, the 100 said feeding devices having a gear in the path of said sliding gears whereby the feeding devices may be operated and reversed, the said lever having a vertically movable fulcrum, and means driven by the saw shaft 105 and controlled by the vertical movement of the lever for raising the saw.

3. In a drop saw machine, the combination with feeding devices, of a saw frame having one end pivotally supported, a saw shaft and saw, a pulley on the saw shaft, 110 an independently driven belt for revolving the pulley, a feed drive shaft, a pulley on said drive shaft, the said belt engaging the pulley and actuating the said drive shaft, gears driven by the said drive shaft and oppositely disposed and arranged to slide thereon, devices for sliding the gears back and forth on the drive shaft including a horizontally movable lever, the 115 said feeding devices having a gear arranged in the path of said sliding gears whereby the feeding devices may be operated and reversed, the said lever having a vertically 120 movable fulcrum, a drum loose on the said saw shaft, a clutch for connecting the drum and saw shaft, a supporting frame, cord pulleys and a cord having a weight at one end and connected with said supporting frame and saw frame and wound upon the 125 130

said drum, and means operated by the vertical movement of the lever for operating the said clutch whereby the saw shaft revolves the drum and draws upon the cord 5 to raise the saw.

4. In a drop saw machine, the combination with feeding devices, of a saw frame having one end pivotally supported, a saw shaft and saw, a pulley on the saw shaft, 10 an independently driven belt for revolving the pulley, a feed drive shaft, a pulley on said drive shaft, the said belt engaging the pulley and actuating the said drive shaft, gears driven by the said drive shaft, 15 and oppositely disposed and arranged to slide thereon, devices for sliding the gears back and forth on the drive shaft including a horizontally movable lever, the said feeding devices having a gear arranged in
- the path of the sliding gears whereby the feeding devices may be operated and reversed, the said lever having a vertically movable fulcrum, a drum loose on the said saw shaft, a clutch for connecting the drum and saw shaft, a supporting frame, cord 25 pulleys and a cord having a weight at one end and connected with said supporting frame and saw frame and wound upon the said drum, a spring-returned clutch-operating arm arranged to act upon the clutch, 30 and a cord connected with the said lever and arm whereby the vertical movement of the lever draws upon said cord to operate said arm and clutch to raise the saw.

In testimony whereof I affix my signature.

CHARLES F. FREAY.
